DESIGN FOR A TEXTILE FABRIC

John G. McCutcheon, Scarsdale, N. Y.

Application July 14, 1938, Serial No. 78,480

Term of patent 3½ years

To all whom it may concern:

Be it known that I, John G. McCutcheon, a citizen of the United States, residing in Scarsdale, in the county of Westchester and State of New York, have invented a new, original, and ornamental Design for a Textile Fabric, of which the following is a specification, reference being had to the accompanying drawing, forming part thereof.

The figure on the drawing is a top plan view of the textile fabric showing my design.

I claim:

The ornamental design for a textile fabric, as shown.

JOHN G. McCUTCHEON.
